ARTHUR JOHNSON, OF MOUNT UNION, PENNSYLVANIA, ASSIGNEE TO ROY P. M.
DAVIS, OF MOUNT UNION, PENNSYLVANIA

BRICKMAKING MACHINE

Application filed July 3, 1928. Serial No. 290,103.

My invention relates to machines for making brick and more particularly to means for placing the molded brick upon the pallets.

5 In the manufacture of brick it has been the practice to fill the open ended mold while the latter is resting upon a cover or liner plate and then transfer the mold from the plate to the pallet by relative horizontal 10 sliding movement of the mold with respect to the plate. This has proven objectionable due to the fact that the brick adheres so closely to the plate that any relative sliding movement of the mold with brick therein, 15 and the plate causes the front lower corner or edge of the brick to become rounded and unfit for use.

The object of my invention is to overcome the objections mentioned by reducing or 20 eliminating this adhesion before effecting relative horizontal movement of the mold and cover plate.

Other and further objects and advantages of my invention will be apparent as the specification is considered in connection with the 25 accompanying drawings, in which:

Figure 1 is a plan view of the device;

Figure 2 is a side view thereof;

Figure 3 is a side view showing the mold 30 elevated and liner plate partially withdrawn; and

Figure 4 is a side view showing the liner plate completely withdrawn and the mold returned to normal position.

35 Referring more particularly to the drawings in which I have illustrated one embodiment of my invention and wherein like reference numerals refer to corresponding parts throughout the several views, 1 denotes a 40 suitable base upon which is mounted an anvil plate or block 3, a pedestal 4 being employed for this purpose. A pallet 5 of any ordinary and suitable construction rests upon and is supported by the anvil plate or block 3, the 45 rolled edges 8 of the pallet extending beyond and below the top face of the block.

Resting loosely upon the top surface of the anvil plate or block 3 is a thin flat smooth liner or cover plate 11, preferably of tin, of 50 sufficient length and width to substantially

cover the pallet. It is upon this plate 11 that the sectional open mold 12 is placed preparatory to the filling and slicking operations, which are performed by any well known and suitable mechanism (not shown).

When the mold 12 has been filled with brick making material and the molded brick have been slicked, the forward edge of the mold is slightly elevated in a manner hereinafter described, and the filled mold is then deposited directly upon the pallet by withdrawing the liner plate from between the mold and pallet, after which operation the mold is stripped from the brick by stripping mechanism (not shown).

The cover or liner plate 11 is withdrawn from between the mold and the pallet by means of a lever 13 pivotally mounted upon the base 1 as at 14, at its lower end, and pivotally connected adjacent the handle portion 15 on its upper end to the rear end of the liner plate as at 16. Any suitable mechanical means (not shown) may be employed to actuate the lever 13, or the latter may be manually manipulated by grasping the handle portion 15 thereof.

In order to reduce or entirely eliminate the adhesion of the brick to the cover or liner plate, the forward edge or side of the mold or the entire mold is slightly elevated before the cover or liner plate is withdrawn. This is accomplished by means of a pair of vertically disposed elevating bars 21 and 21', the upper ends of which extend through guides 22 and 22' secured to the anvil plate or block 3. The lower ends of these bars 21 are pivotally connected to the forward ends of a pair of levers 23 and 24 in turn fixedly mounted upon a shaft 25. This shaft 25 is rotatably supported at its ends in bearings 26 and 26' 40 mounted upon the base 1. The lever 23 is formed with a rearwardly extending arm or extension 27 which is provided at its end with a foot treadle 28. Depression of the foot treadle 28 rocks the shaft 25 and levers 23 and 24 in an anti-clockwise direction, thus elevating the levers 21 and 21' until the upper ends of these levers 21 and 21' engage the extended ends 29 and 29' of the forward bar or side member 30 of the mold 12.

45 50 55 60 65 70 75 80 85 90 95 100

Further depression of the foot treadle slightly elevates the forward side of the mold and reduces or eliminates the bond between the brick and cover plate thereby reducing to a minimum the danger of distorting the brick at its forward edge or corner during the withdrawal of the cover plate. The mold is held against movement during the withdrawal of the cover plate, by means of fingers or extensions 31 and 31' formed on the respective upper ends of the levers 21 and 21' which engage behind the inner face of the extended ends 29 and 29' of the front side member 30 of the mold.

Where brick making materials (mud) of certain kinds are employed it has been found advisable to lubricate the top of the cover or liner plate by sprinkling with sand or other suitable material. The use of such lubricant together with the tilting operation effectively eliminates or reduces adhesion of the "mud" to the plate.

It will of course be understood that the same danger of damage to the brick due to rounding of the forward corner or edge is present when the mold is pushed across the face of the cover plate as distinguished from the mechanism disclosed wherein the cover plate is withdrawn from beneath the mold. I therefore wish it to be understood that my invention contemplates relative movement of the mold and cover plate.

Having thus described my invention what I claim as my invention is:

1. A brick making machine comprising a support adapted to support a mold plate with filled mold thereon and a pallet, means for slightly elevating one edge of the mold with respect to the corresponding edge of the plate to reduce adhesion between the brick and plate, and means for causing relative horizontal movement of the mold and plate, whereby the filled mold will be deposited upon the pallet.

2. A brick making machine comprising a support adapted to support a mold plate with filled mold thereon, means for causing relative separation in a vertical plane of one edge of the mold from the corresponding edge of the plate, and means for causing relative horizontal movement of the mold and plate whereby the filled mold will be deposited upon the pallet, the operation of said last mentioned means being entirely independent of the operation of said first mentioned means.

In testimony whereof I affix my signature.
ARTHUR JOHNSON.
